WARM AIR FURNACE

Alonzo W. Gearhart, Fresno, Calif.

Application May 25, 1935, Serial No. 23,444

2 Claims. (Cl. 110—86)

My invention relates to a warm air furnace, and more specifically to that form of furnace in which hydrocarbon fuel is used. With slight modifications other forms of fuel may be used. 5 An object I have accomplished in my invention is the construction of a furnace having a down draft passage for excess burnt gas and smoke in which the maximum heat units produced by combustion within the furnace is controlled, as against 10 loss of a large per cent of the heat units in furnaces as now constructed. Another object is that the entire area of the furnace wall is used as a means to radiate heat. Other objects will be hereinafter disclosed.

15 In the drawing herewith which is hereby made a part of this specification, Fig. 1 is a front sectional view of a furnace constructed with my invention incorporated therein.

Fig. 2 is a sectional view of the furnace, at 20 right angles to the view shown in Fig. 1, along section lines 2—2 in Fig. 1.

Fig. 3 is a cross sectional view of the furnace along the sectional line 3—3 in Fig. 1, viewing the device from the top.

25 Fig. 4 is a perspective view of the furnace with parts cut away to show portions of the inside of the device.

Referring to the drawing, the furnace has an 30 enclosed chamber 6. This chamber is shown rectangular in form in the drawing, having four upright walls designated 61, 62, 63 and 64; a bottom 65, and a top or cover 66. Other shapes can be adapted to my invention. Near the bottom of 35 wall 61 is inlet opening 7 for admission of fuel into combustion chamber 9. The fuel preferred in the form shown in the drawing is fuel oil, but natural gas, artificial gas, or any form of hydrocarbon fuel may be used.

A flue opening 8 is positioned preferably on 40 wall 64, on a horizontal plane above the opening for the fuel intake. Wall 64 is opposite to wall 61. Flue 8 is intended for disposing of the burnt gas of combustion.

Combustion chamber 9 is located within the 45 enclosed chamber and at the bottom thereof. The combustion chamber consists of a bottom 91, which can be positioned on the bottom of enclosed chamber 6, a back 92, which should be positioned on a plane approximately parallel with 50 side 64, and a spaced distance therefrom, and ends 93 and 94, which ends should be on parallel planes with sides 62 and 63, and a spaced distance from each of said sides. It is noted that the combustion chamber is open at the top and is 55 positioned so that inlet 7 opens into it. The

combustion chamber is relatively high enough to be on a plane with the lower end of the flue. These relative proportions are not arbitrary, and slight changes can be made therein without departing from the spirit of my invention. 5

I have placed a baffle plate 10 back of the combustion chamber. This baffle plate is preferably attached to wall 64 just above the flue and extends downwardly at an angle to the back wall of the combustion chamber, thus forming a closure for the space within the enclosed chamber which is between the wall 64 and the back 92. This baffle plate further comprises extensions 101 and 102 on each side of the combustion chamber and within the space between the combustion 10 chamber ends 93 and 94, and chamber walls 62 and 63. Such extensions end a spaced distance from wall 61. The spaces, or openings between wall 61 and said extensions 101 and 102, are designated 103 and 104. 15

The portion of the enclosed chamber above the baffle can be termed the upper compartment, and the portion below the baffle the lower compartment. 20

The arrows 13 show the circuits naturally followed by the heated currents constituting the products of combustion. It is noted that naturally the flame and heat produced in the combustion chamber will pass upward until it is deflected by the ceiling of the chamber. From thence 25 it will spread along the lines of least resistance over the upper portion of the enclosed chamber, and then down the sides of the enclosed chamber in the upper compartment until it strikes the baffle. The only outlet for the burnt gas and 30 accompanying heat which is not radiated is in the lower compartment just under the baffle, and the pathway such burnt gas and heat must travel is through openings 103 and 104 then to the back 35 of the combustion chamber in the lower compartment, under the baffle, and out of flue 8. It will be noted that the path of travel of the heat and burnt gas from the upper compartment to the lower compartment is much longer than in 40 furnaces of ordinary construction, and the heat is retained longer within the furnace or enclosed chamber before it can be released by the flue, thus giving the opportunity to radiate more heat from the products of combustion. 45

It is noted that the walls comprising chamber 6 are preferably constructed of sheet metal which is adapted to transmit heat to the outside of the furnace. An outside wall 15 is placed around the furnace a spaced distance therefrom and the 50 heat radiated through the metal wall of the en- 55

closed chamber is transported by means of pipes leading from the space between the enclosed chamber walls and the outside wall to the places desired.

5. It is noted that the same general principles herein set forth can with slight modification for fitting the parts be applied to a tubular furnace or those of other shapes.

The outlets for the heated air to be used are 10 designated 19. The furnace door is designated 20.

Having described my invention I claim as new and ask for Letters Patent:

1. In a furnace having a closed combustion chamber, a fire box in the lower part of the combustion chamber, said fire box being spaced from the sides and rear of said combustion chamber, said spaces between the walls of the combustion chamber and the walls of the fire box being enclosed with a sloping partition extending from the rear wall of the combustion chamber to the upper end of the rear wall of the fire box, and transversely across said combustion chamber, said partition further extending along the side walls of the fire box and the side walls 25 of the combustion chamber to a spaced distance from the front wall of the combustion chamber

and a spaced distance from the floor of the combustion chamber, and a flue opening from the combustion chamber directly under said sloping partition.

2. In a furnace having a closed combustion chamber, a fire box open at the top, the sides and back thereof being spaced from the sides and back of the combustion chamber, and the front wall of the fire box being adjacent to the front wall of the combustion chamber, said fire box being located at the bottom of said combustion chamber, a baffle plate extending transversely across the combustion chamber from the top of the back of the fire box sloping upward to the back wall of the combustion chamber, and downward on either side of the fire box to within a spaced distance from the front wall of the combustion chamber and a spaced distance from the floor of the combustion chamber, an opening in the combustion chamber adapted as a flue located 15 under and adjacent to the baffle plate, and an opening in the front wall of the combustion chamber and fire box adapted to admit fuel into the fire box.

ALONZO W. GEARHART. 25
